The ornamental design for a fluid test strip, as shown and described.

DESCRIPTION

FIG. 1 is a perspective view of a fluid test strip;
 FIG. 2 is a top plan view of the fluid test strip of FIG. 1;
 FIG. 3 is a right side elevational view of the fluid test strip of FIG. 1;

FIG. 4 is a left side elevational view of the fluid test strip of FIG. 1;

FIG. 5 is a bottom plan view of the fluid test strip of FIG. 1;

FIG. 6 is a front elevational view of the fluid test strip of FIG. 1; and,

FIG. 7 is a rear elevational view of the fluid test strip of FIG. 1.

The broken lines are included for the purpose of illustrating unclaimed portions of the fluid strip test and form no part of the claimed design. The cross-hatching patterns of the article indicate surface character.
